UNITED STATES PATENT OFFICE.

SIDNEY T. SJOBERG, OF MINNEAPOLIS, MINNESOTA.

FUSE-PLUG.

1,330,499.

Specification of Letters Patent. Patented Feb. 10, 1920.

Application filed January 17, 1917. Serial No. 142,810.

To all whom it may concern:

Be it known that I, SIDNEY T. SJOBERG, a citizen of the United States, resident of Minneapolis, county of Hennepin, State of Minnesota, have invented certain new and useful Improvements in Fuse-Plugs, of which the following is a specification.

My invention relates to multiple fuse plugs and the object of the invention is to improve the type of plug shown and described in my pending application for Letters Patent of the United States, Serial No. 79,488, filed February 21, 1916.

A further object is to provide a multiple fuse plug of extremely simple construction and one which can be manufactured at a low cost.

The invention consists generally in various constructions and combinations, all as hereinafter described and particularly pointed out in the claims.

In the accompanying drawings forming part of this specification,

Figure 1 is a longitudinal sectional view through a fuse plug embodying my invention,

Fig. 2 is an outside view with the wall of the fuse plug broken away,

Fig. 3 is a horizontal sectional view on the line 3—3 of Fig. 1,

Fig. 4 is a similar view on the line 4—4 of Fig. 1,

Fig. 5 is a plan view, showing the means for indicating when a certain fuse has burned out,

Fig. 6 is a sectional view on the line 6—6 of Fig. 1,

Fig. 7 is a sectional view of the top of the fuse plug, showing a burned out fuse and an indicating means therefor in the cap of the plug.

In the drawing, 2 represents one member of the plug and 3 another member, both composed of insulating material, preferably porcelain. These members have a central orifice 4 extending therethrough to receive a contact pin 5, the members revolving on the pin to shift the circuit from one fuse wire to another. This pin has at its inner end a head 6 forming a contact surface and an insulating washer 7 is interposed between this head and the shell contact 8 to prevent possibility of arcing at this point, said shell contact being threaded to receive the end of the insulating member 2, as usual in plugs of this type, and a tongue 9, of

suitable conducting material forming a spring contact, is mounted at one end on the shell contact 8 and projects upwardly through a hole 10 in the flanged upper end 60 of the member 2 and into a recess 11 that is formed in the lower end of the plug member 3, the walls of said recess depending and encircling the upper end of the tongue or spring contact. The member 3 is provided with a plurality of holes or sockets 12 therein, extending through the same from end to end and communicating at one end with the recess 11 and there may be any desired number of these holes according to the 70 number of fuse wires to be used.

13 represents the fuse wires, each having a cap 14 at one end, preferably concave in form, fitting into the inner end of a socket 12 adjacent to the recess 11, the fuse wires 75 extending centrally through the sockets and having their opposite ends soldered to radially projecting lugs 15 formed on a head 16 of the pin 5 and seated within a recess 17 in the end of the member 3. The lugs 80 15 seated in sockets 16 in the end of the member 3 prevent the pin 5 from turning independently of the member 3 and breaking the fuse connections between them. These two parts of the plug must turn together in 85 the operation of shifting the contact from one fuse wire to another.

Between the sockets 18 the member 3 is provided with insulating partitions 19 separating the socket of one fuse wire from all 90 the others and forming a series of independent chambers 20 in the end of the member 3. A metallic cap 21 is fitted over the end of the member 3 in any preferred manner. A disk 22 of mica, or similar material, is 95 interposed between the cap 21 and the top of the partitions 19, and the cap 21 has a series of openings 23 therein through which and the sheet of mica the fuse wire sockets may be visible. The under surface of the 100 sheet of mica or other transparent material will be discolored where its surface is exposed to the smoke of the fuse wire in the chamber to indicate that the fuse or connection in that chamber has burned out. 105

In Fig. 7 a modification is shown, in which a disk 24 of suitable material has holes 25 therein in which wafer-like members 26 of a suitable fusible material are inserted. When a fuse wire burns out, the heat will 110 melt the wafer and indicate the exact position of the burned out fuse.

2
 To enable the operator to determine the position of the contact spring or tongue, I prefer to provide a projection or indicator 27 on the member 2 opposite the contact surface of the tongue, so that when the member 3 is revolved and the tongue travels from one fuse contact to another the indicator will make a corresponding movement and the operator, preparatory to adjustment of 10 the plug, can instantly determine the exact position of the contact spring and the member of the fuse by the markings on the outer surface of the plug.

An essential characteristic of a fuse plug 15 of this type is a construction in which there will be no danger of arcing and at the same time an article of this kind to be salable must be capable of economical manufacture. Unless the plug is of the character described, it cannot enter into extensive use or 20 successfully pass the underwriters' tests.

I claim as my invention:

1. A multiple fuse plug comprising a contact pin, insulating members mounted for 25 relative rotation thereon, a head secured to said pin, fuse wires connected to one end of said head and having contact surfaces in one of said members, a shell contact mounted on the other member and having means 30 for engaging the contact surfaces of said fuse wires successively as said members are relatively rotated, a cap for concealing one end of one of said members and having openings therein corresponding in number 35 to the number of said fuse wires, and partitions radiating from said pin adjacent to

the point of connection with said fuse wires and dividing the spaces between said fuse wires and said cap into a series of independent chambers, the openings in said cap leading to said chambers respectively, a transparent disk seated on said partitions and held thereon by said cap and closing the openings in said cap, the burning out of a fuse wire being indicated on the part of 40 said disk closing the opening leading to the chamber in which the burned fuse is mounted.

2. A multiple fuse plug comprising a contact pin, insulating members mounted thereon for relative rotation, one of said members having a series of fuse wires mounted at intervals therein and provided with contact surfaces, the other member having a head at its inner end for contact with said first 50 member and provided with a smaller outer end, a shell contact fitting said smaller outer end and having a tongue member projecting through said head for engagement with said contacting surfaces successively when said members are revolved, and an indicating device formed on said head and bridging the joint between it and the other insulating member opposite and adjacent the contacting surfaces of said tongue member and 55 forming an exterior indicator to determine the position of said tongue member with respect to said contact surfaces.

In witness whereof, I have hereunto set my hand this 12th day of January, 1917.

SIDNEY T. SJOBERG.
